CLAIM

The ornamental design for a vertical fore grip and bipod, as shown and described.

DESCRIPTION

FIG. 1 is a top, front, and right side perspective view of a vertical fore grip and bipod showing our new design;

FIG. 2 is a bottom front and right side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top, front, and right side perspective view of a vertical fore grip and bipod showing our new design with the bipod legs in an extended condition;

FIG. 10 is a bottom front and right side perspective view of FIG. 9;

FIG. 11 is a front elevational view of FIG. 9;

FIG. 12 is a rear elevational view of FIG. 9;

FIG. 13 is a right side elevational view of FIG. 9;

FIG. 14 is a left side elevational view of FIG. 9;

FIG. 15 is a top plan view of FIG. 9; and,

FIG. 16 is a bottom plan view of FIG. 9.

The broken lines are for illustrative purposes only and form no part of the claimed design.
